UNITED STATES PATENT OFFICE.

HARRY C. ZIMMERMAN, OF WASHINGTON, DISTRICT OF COLUMBIA.

MOUNTING FOR PUMPS.

Application filed September 11, 1924. Serial No. 737,176.

(GRANTED UNDER THE ACT OF MARCH 3, 1883; 22 STAT. L. 625.)

To all whom it may concern:

Be it known that I, HARRY C. ZIMMERMAN, a citizen of the United States, and a resident of Washington, District of Columbia, have invented an Improvement in Mountings for Pumps, of which the following is a specification.

The invention described herein may be used by the Government, or any of its officers or employees in prosecution of work for the Government, or by any other person in the United States, without payment to me of any royalty thereon, in accordance with the act of March 3, 1883.

15 The subject of this invention is a mounting for pumps.

The purpose of the present invention is to provide means for conveniently attaching a pump to a gun when replenishing hydro-pneumatic recoil mechanisms with oil. As the normal pressure within the recoil chamber is considerable, the filling device for adding new oil must exert a correspondingly greater unit pressure; consequently, it has been customary to use screw pumps or fillers and a separate bracket either permanently or removably attached to some part of the gun is provided to securely hold the filler when in operation.

30 Accordingly, it is proposed to removably mount the pump on a convenient and accessible member of the gun without the aid of brackets or other independent supporting means and to provide a flexible hose for connecting the pump to the recoil chamber.

To these and other ends, my invention consists in the construction, arrangement, and combination of elements, described hereinafter and pointed out in the claims 40 forming a part of this specification.

A practical embodiment of my invention is illustrated in the accompanying drawing, in which,

45 Fig. 1 is a view in side elevation of the rear end of a gun, showing the pump mounted for operation; and

Fig. 2 is a sectional view on the line 2—2 of Fig. 1.

50 Referring to the drawing by numerals of reference:

According to the invention, a gun barrel 11 is reciprocally mounted on a cradle 12

within which is a hydro-pneumatic recoil chamber 13. Mounted as permanent equipment on the breech end of the barrel is a vertical casing 14 which encloses operating elements for the breech block mechanism.

This casing is utilized for mounting a pump or screw filler 15 having the usual piston 16 which is turned by means of a lever handle 17.

The casing 14 is formed with a rib 18 having a longitudinal dove-tail groove 19 for receiving a complementary tongue 20 formed on the filler 15. Any suitable device 65 for limiting the downward movement of the filler may be provided, specifically a pin 21 extending transversely across the lower end of the slot 19.

A more or less flexible tube 22 is provided 70 with coupling unions 23 at either end for securing the hose to the filler and the filling hole in the recoil chamber.

After replenishing the recoil chamber the filler is removed and a plug placed in the 75 filler hole.

It is obvious that instead of forming the rib on the casing a bar properly slotted or grooved may be secured thereon.

While in the foregoing there has been 80 illustrated and described such combination and arrangement of elements as constitute the preferred embodiment of my invention, it is nevertheless desired to emphasize the fact that interpretation of the invention 85 should only be conclusive when made in the light of the subjoined claims.

I claim:

1. The combination with a gun having a groove therein, of a pump formed with a 90 complementary tongue for removably mounting the pump on the gun, a stop disposed in the slot, and a flexible tube removably connected to the pump and the gun.

2. The combination with a gun having a 95 groove therein, of a pump formed with a complementary tongue for removably mounting the pump on the gun, and a stop extending transversely across the slot.

3. The combination with a gun having a 100 groove therein, of a pump formed with a complementary tongue for removably mounting the pump on the gun.

HARRY C. ZIMMERMAN.
